UNITED STATES PATENT OFFICE.

ALBERT J. D. OHM, OF ASTORIA, NEW YORK, ASSIGNOR TO LION ELECTRIC MANUFACTURING COMPANY, INC., A CORPORATION OF NEW YORK.

DESIGN FOR A RING BODY FOR LAMP FIXTURES.

Application filed October 20, 1923. Serial No. 7,560. Term of patent 3½ years.

To all whom it may concern:

Be it known that I, ALBERT J. D. OHM, a citizen of the United States of America, residing at Astoria, county of Queens, and State of New York, have invented a new, original, and ornamental Design for Ring Body for Lamp Fixtures, of which the following is a specification, reference being had to the accompanying drawing, forming part thereof.

The figure is a perspective elevation of the ring body for lamp fixtures.

I claim:—

The ornamental design for a ring body for lamp fixtures as shown.

ALBERT J. D. OHM.

Witnesses:

JOSEPH T. McMAHON,
VIRGINIA W. FALLER.
